UNITED STATES PATENT OFFICE.

JAMES A. CAREY, OF NEW YORK, N. Y., ASSIGNOR TO STANDARD STOKER COMPANY, INC., OF NEW YORK, N. Y., A CORPORATION OF DELAWARE.

AUTOMATIC STOKING MECHANISM.

1,344,578.

Specification of Letters Patent. Patented June 22, 1920.

Application filed April 3, 1919. Serial No. 287,279.

To all whom it may concern:

Be it known that I, JAMES A. CAREY, a citizen of the United States, residing at New York city, in the county of New York 5 and State of New York, have invented certain new and useful Improvements in Automatic Stoking Mechanisms, of which the following is a specification.

This invention is an improvement in 10 means for reducing by pressure lumps of coal to or below a given size while advancing the same, and its object is to increase the efficiency of that type of such a means as is shown in the patent to David T. Williams, 15 No. 1,152,682 by eliminating the excessive downward pressure of the fuel overlying the region where the crushing or reducing is taking place and the consequent undue resistance to the fuel advancing screw or 20 equivalent.

My invention is fully illustrated in the accompanying drawing, wherein,

Figure 1 is a longitudinal sectional view of a fuel-reducing means (the particular 25 type shown being that illustrated in the said Williams patent) having my improvement; and

Figs. 2, 3 and 4 are a plan, an elevation viewed from the rear and a side elevation 30 of a structure directly embodying the salient features of my invention.

a designates the forward part of the trough at the bottom of the bunker of a locomotive tender or other container for the 35 mass of fuel; *b* the front wall of such trough, the same being cut away at *c* to form an opening through which the coal may be advanced and thence conveyed by any suitable means to and distributed over 40 the locomotive furnace and grate; and *d* a rotary screw extending longitudinally of and over the bottom of the trough and preferably into said opening and adapted to be rotated by some suitable means (not 45 shown).

e is a plate which is bolted flat against the inside of the front wall *b* of the trough, having an opening *f* to register with the opening *c*. This plate has the rearwardly 50 projecting spurs or lugs *g* which are illustrated in the said Williams patent and therein described as acting partly to split or cleave the lumps of coal which are too large to be forced by the screw through the opening *c* without reduction and partly to

keep them in position to be crushed between the screw and the abutment formed by the plate, or be ground down by the screw to a size permitting them to pass through said opening.

Above the spurs or lugs *g* I provide on the plate, also projecting rearwardly, the studs or prongs *h*. These are appreciably longer and are preferably somewhat stockier or thicker than the spurs or lugs *g*, and in 60 the best form taper from their bases toward their free ends, with a somewhat sharper taper at their extremities, being polygonal in cross-section and presenting each a rather sharp edge at the under side adjoining the 65 screw; they are arranged in the adaptation illustrated in an arch substantially concentric with the axis of the screw. Between the spurs or lugs *g* and these studs or prongs *h* are arranged on the plate other studs or 70 prongs *i* somewhat longer than the former but shorter than the latter and preferably arranged in staggered relation to the studs or prongs *i*.

Now when the bunker is well filled with 80 coal the studs or prongs *h*, by forming a kind of shelf or ledge for the mass of coal above it and next to the forward support for the coal formed by the wall *b* and plate *e*, prevent the weight of this portion of the coal 85 from causing an undue packing of the coal in the region where the fixed abutment (formed by the plate and its studs *g*) and the moving abutment (formed by the screw) are effecting the reduction of the unduly 90 large lumps, whereby not only is the possibility of jamming reduced but a considerable part of the resistance otherwise imposed on the motor for driving the screw 95 eliminated. By comprising spaced members *h* this shelf or ledge has more specifically the character, as it were, of a grate, the spaces between the studs or prongs not only permitting the smaller fragments of coal to work down through but a certain amount of 100 upward yield in the mass of coal beneath the shelf or grate, thus further to avoid packing in the region where the reducing is going on. It is not essential that the studs or prongs be shaped as herein described, 105 though the shape specified I have so far found preferable in actual practice of the invention.

The studs or prongs *i* are not indispensable. But I prefer to employ them for this 110

reason: The studs or prongs *h*, it will usually be found, should be spaced a certain distance from the screw so that flow of coal may take place toward the opening *c* between them and the screw, and with the studs or prongs *i* or their equivalents present, the coal is prevented from becoming pocketed between the studs or prongs *h* and the spurs or lugs *g*. Being somewhat longer than the spurs or lugs *g*, and also sharpened, they prevent the larger lumps from slipping upwardly out of the influence of the screw and said spurs or lugs, and also act directly more or less in the actual reducing of the fuel.

It will be understood that the level of the coal is considerably higher than is shown in Fig. 1 when the bunker is full, *i. e.*, when the downward pressure of the fuel at the point where the reducing takes places is sufficient to be taken into account and that

to support the mass of fuel above the front wall of the trough removable planking and gates, shown in the Williams patent but not appearing herein, or their equivalents are 25 usually employed.

Having thus fully described my invention, what I claim as new and desire to secure by Letters Patent is:—

In combination, means to advance fuel from the bottom of a fuel mass in a substantially horizontal course, and abutment means for the fuel arranged over and spaced from the first means and relatively forward of the fuel, said means including projections extending rearwardly and arranged at different elevations and each upper projection extending farther rearward than those below it.

In testimony whereof I affix my signature April 1st, 1919.

JAMES A. CAREY.
